UNITED STATES PATENT OFFICE.

WILLIAM H. BATEMAN AND FRANCIS X. HOOPER, OF BALTIMORE, MD.

PRINTER'S GALLEY.

SPECIFICATION forming part of Letters Patent No. 231,525, dated August 24, 1880.

Application filed November 10, 1879.

To all whom it may concern:

Be it known that we, WILLIAM H. BATEMAN and FRANCIS X. HOOPER, both of Baltimore city, State of Maryland, have invented 5 certain new and useful Improvements in Printers' Galleries; and we hereby declare the same to be fully, clearly, and exactly described as follows, reference being had to the accompanying drawings, in which—

10 Figure 1 is a perspective view of the device; Figs. 2 and 3, respectively, top and bottom plans of the corners; Fig. 4, a sectional view on line $x x$, Fig. 3.

15 Our invention has reference to printers' galleries for holding type; and it has for its object to produce a galley embodying in maximum degree the attributes of lightness and strength.

Our invention consists in a galley having 20 tubular walls secured to a base-plate and reinforced at the corners by a metallic filling, as hereinafter set forth.

In the accompanying drawings, A is the base-plate, and B the tubular walls, the cross-section of the latter being a right-angled isosceles triangle having its acute angles truncated, forming edges $b b'$, which receive any 25 accidental blows and prevent the walls from being battered or indented. These walls are secured to the base-plate by means of screws 30 E, the open ends being plugged with wood, as shown, to prevent entrance of dirt, &c.

In forming the galley the tubes are mitered at the corners, and in each is placed a plug, C, of cork or wood or other suitable material. The walls being screwed to the plate, type-metal, lead, solder, or other suitable readily-fusible metal is poured through holes d until the space between the plugs C is completely filled, thereby connecting the walls at the corners by means of a solid metallic filling, which 35 not only secures them together, but to the base-plate also, as the screws E are embedded in the metal, and the latter fills the holes d flush with the surface of the base-plate.

It will be readily understood that the joint 40 leaves nothing to be desired in point of strength.

Before running in the filling the inside of the tubes may be tinned, if desired, when a 45 perfect adhesion of the filling thereto will be insured; but this is scarcely necessary.

What we claim is—

The galley herein described, having tubular walls B, provided with plugs C, screws E, and filling cast through holes d, substantially as 50 set forth.

WM. H. BATEMAN.
FRANCIS X. HOOPER.
